[57] CLAIM

The ornamental design for a sign, as shown and described.

DESCRIPTION

FIG. 1 is a perspective view of the sign according to the present invention;

FIG. 2 is a front elevational view thereof;

FIG. 3 is an elevational view of one side of the sign the other side being substantially identical thereto;

FIG. 4 is a rear elevational view thereof;

FIG. 5 is a top plan view;

FIG. 6 is a bottom plan view;

FIG. 7 is a perspective view of an alternative embodiment of the invention;

FIG. 8 is a front elevational view of the alternative embodiment the other views being substantially the same as the views of the preferred embodiment in FIGS. 3-6;

FIG. 9 is a perspective view of a second alternative embodiment of the invention; and,

FIG. 10 is a front elevational view of the second alternative embodiment the other views being substantially identical to the views shown in FIGS. 3-6 of the preferred embodiment.
